UNITED STATES PATENT OFFICE.

ALBERT E. JOHNSON, OF BROCKTON, MASSACHUSETTS, ASSIGNOR TO UNITED SHOE MACHINERY COMPANY, OF PATERSON, NEW JERSEY, A CORPORATION OF NEW JERSEY.

MACHINE FOR MAKING INSOLES.

1,109,759.

Specification of Letters Patent.

Patented Sept. 8, 1914.

Application filed May 14, 1908. Serial No. 432,765.

To all whom it may concern:

Be it known that I, ALBERT E. JOHNSON, a citizen of the United States, residing at Brockton, in the county of Plymouth and 5 State of Massachusetts, have invented certain new and useful Improvements in Machines for Making Insoles; and I do hereby declare the following to be a full, clear, and exact description of the invention, such as 10 will enable others skilled in the art to which it appertains to make and use the same.

This invention relates to machines for forming insoles, and more particularly to machines for forming what are known commercially as "economy" insoles.

In making economy insoles the blank is treated by slitting its face to form a channel and by slitting its edge to form a feather, the slitting operations thus producing 20 two independent flaps. These two flaps are then turned up from the channel and the feather and are brought together to form a single, compound lip. Thereafter reinforcing material, such as canvas, may 25 be applied to the insole and to the lip thus formed.

The present invention contemplates an improvement in the formation of insoles of the general character described and relates 30 particularly to the step of bringing the channel and feather flaps together to form a single, compound lip.

Heretofore various attempts have been made to insure the retention of the two upturned flaps in intimate contact, principally 35 by the use of cement applied to the upper surfaces of the flaps, which become their inner surfaces after being upturned. Such a method of procedure is inefficient, however, as it has been found that with certain 40 grades of stock cement does not insure a permanent contact of the two flaps.

The principal object of this invention is to provide means for permanently securing 45 together the two contiguous channel and edge flaps of an insole. This object of the invention may be attained by upturning the two flaps of an insole of the type described and applying thereto a series of fastening 50 devices acting to bind the flaps together, the devices being of such a nature as to insure permanence of contact between the flaps. A convenient and efficient manner of

providing the desired permanence of contact between the two flaps is by employing 55 fastening devices which may be inserted in the two flaps, for instance, by being passed through said flaps. The fastening devices may be connected together or formed from a continuous material, and in the preferred 60 embodiment of the invention said devices comprise stitches formed from a continuous piece of suitable fastening material, such as wire or thread. It should be distinctly understood, however, that the invention is 65 not limited in its scope to the use of a continuous fastening material, but includes the use of any fastening device applied to the independent flaps to bind them together in upturned position and thus form a permanent 70 compound lip projecting from the face of the insole.

For convenience, the invention has been shown embodied in the type of channeling machine fully illustrated and described in 75 the U. S. Letters Patent to William C. Meyer, No. 984,773, issued Feb. 24, 1911. In that machine the knives for slitting and channeling the insole are constructed and arranged to act as plows to turn up the 80 flaps as they are formed and hold them in upturned position, and the present invention in its specific embodiment combines with these devices a sewing attachment conveniently mounted and timed as to its operation to stitch the flaps together during 85 the cutting and upturning operations. Preferably the flaps are secured together by means of a single thread stitch, conveniently a chain-stitch, but as it is believed that 90 it is broadly new to upturn and secure together the two flaps of an insole by means of a line of fastenings, the invention is not limited to the use of any particular form of stitch.

Means is provided to sever the thread when the stitching is completed. This means comprises a knife which is in inoperative position while the line of stitches is being formed, but is brought forward into 100 operative position at the completion of the stitching operation. Preferably the operating movement of the knife is controlled by the lowering of the work support to permit removal of the work.

In addition to the objects of the inven-

95

100

105

tion above referred to, the invention also consists in certain constructions and arrangements of parts as fully set forth hereinafter, the advantages of which will be 5 obvious to those skilled in the art.

To the accomplishment of these objects the invention comprises the features and combinations of parts hereinafter described, and particularly pointed out in the appended claims.

The various features of the invention will be best understood from a description of one embodiment thereof, such, for instance, as illustrated in the accompanying drawings, 10 in which:

Figure 1 is an elevation of the left-hand side of the channeling machine of the patent to William C. Meyer hereinbefore referred to, in which the present improvements are embodied; Fig. 2 is an enlarged detail, in elevation, of the present improvements viewed from the right-hand side of the machine; Fig. 3 is a front elevation of the parts shown in Fig. 2, a portion of said parts, however, being shown in section on the dotted line $z-z$, Fig. 2; Figs. 4 and 5 are diagrammatic elevational views similar to Fig. 2, but with the channel knife and presser-foot removed, showing different 20 steps in the formation of a stitch; Fig. 6 is a detail in section on the line $y-y$ of Fig. 4, the presser-foot, however, being also illustrated; Fig. 7 is a diagrammatic view with the parts of the stitching mechanism in 25 similarly related positions, as shown in Fig. 4, but viewed from the opposite side of the machine; and Fig. 8 is an enlarged detail in perspective of the needle and its related parts viewed from an inside position.

In the present instance the invention has been shown as applied to the usual machine for forming a channel and feather on an insole by cutting channel and feather flaps and then upturning said flaps toward each other to form together a single, compound lip. In this type of machine, a channel knife 1 is utilized, which is provided with a horizontal cutting edge, and a plow 2 at its lower end for turning up the channel flap (see Fig. 8). This knife is mounted in an oblique groove in a knife block 3 (Fig. 2) which is supported upon a knife frame 9 projecting forwardly from a vertically movable support or shank 25 extending upwardly through a guideway 26 conveniently formed in the frame of the machine. The shank of the knife 1 extends across the sole and lies in a plane at substantially right angles to the portion of the edge of the sole 50 which is being operated upon. An edge or feather knife 11 (Fig. 6) is also provided, the shank of which extends longitudinally of the sole and lies in a plane substantially at right angles to the plane of the shank of 55 the channel knife 1. The shank of this

knife is arranged obliquely to the face of the sole, and therefore it also acts as a plow to turn up the feather flap in the formation of the insole (see Fig. 8). The edge knife 11 is mounted in an oblique groove in a knife block 12 (Figs. 1 and 3), which knife block in turn is carried on the knife frame 9 by means of a tongue-and-groove connection 15 (Fig. 7). The construction and mounting of the knives is such that at the time 70 the flaps are cut they are upturned and are held by the knives in upturned position. Both knives are capable of vertical movement toward and away from the insole in the guideway 26 to accommodate any unevenness in the sole stock, but are held in their lowermost position and in contact with the sole by means of a suitably arranged spring 31 having a lower bearing against a lug projecting from the shank 25 and an upper 80 bearing against a lug projecting from the guideway 26. The sole is supported upon a work table 35 on a stem 36 mounted in a vertically movable slide 37 on a bracket 38 which, as usual, may be lowered from the 90 knives for insertion and removal of the sole. The table 35 is rotatably mounted on the stem 36 to assist in feeding the work. A positive, step-by-step rotation is imparted to the work table by means of a friction 95 clutch 67 having motion imparted to it by means of suitable connections with a cam groove 75 in a cam disk mounted on the main shaft 51. The work is fed past the knives and across the support or table 35 100 by a feeding foot (not shown) to which is imparted a four-motion feeding movement. The vertical motion of the feeding foot is obtained from a cam groove in a disk 52 on the shaft 51 which is connected by means 105 of a suitable train of mechanism to the bar on which the feed foot is mounted. The transverse or feeding movement is imparted to the feeding foot by means of an eccentric (not shown) at the forward end of the 110 driving shaft 51, and operably mounted in the supporting bar for the feeding foot. Rotation of the work support slide 37 is prevented by a pin 121 (Fig. 1) passed through a lug 120 in the slide and into the frame. 115

All of the parts just described may be and preferably are substantially similar to the parts designated by the same numerals in the patent to William C. Meyer hereinbefore referred to. The channel and feather 120 knives are held in working position and are provided with similar adjustments to suit the varying necessities of the work operated on in a manner substantially as shown in the patent to said William C. Meyer, except with respect to the adjustability of the knives hereinafter described in detail.

All of the parts heretofore described are mounted in a suitable frame F sustained on a supporting base or stand S. The driv- 125

ing shaft 51 is rotated by a rope belt from any convenient source of power, passing over a suitable sheave or pulley P.

Referring now to the novel features comprised in this invention, in the embodiment selected for illustrative purposes, a spool or bobbin of thread for use in making a stitch is held in a receptacle 27 (Fig. 1), sustained by a bracket 28 mounted in the

10 upper portion of the frame F. The thread from the bobbin is carried through a guide 29 and given a turn around a convenient form of tension truck 30, journaled at 32 in the bracket 29, and is thereafter carried 15 downwardly and passed through a thread guide 39 (Figs. 4 and 5) on the knife frame 9. The disk 52 is provided with a second cam groove 40 (Fig. 1) which is engaged by a cam roll 41 mounted upon a lever 42 20 fulcrumed at 43 on the frame F. The free end of the lever 42 is connected by an adjustable pin-and-slot connection 44 to one end of an adjustable link 45, the other end of which is pivoted to a lever 46 fulcrumed 25 by its upper end on a pin 47 (Figs. 2 and 3) extending from the upper end of the vertically movable shank 25 which supports the edge and channel knife frame 9. The lower or free end of the lever 46 is provided with a 30 boss 48 (Figs. 3 and 7), at the inner side of which is mounted a needle carrier 49 having suitably secured at its lower end a barbed needle 50 of the usual type for making a chain-stitch. The needle 50 is slightly 35 curved, and extends along the arc of a circle having the center of the pivot 47 as a center so that it may act properly upon the work.

The boss 48 at the lower end of the lever 46 is provided with a transversely arranged groove 46^a (Fig. 3) into which projects a supporting lug 53 of a slide 54 adapted to move in a horizontally arranged recess 55 of the knife frame 9. A hole 56 (see Fig. 6) is cut in the inner end of the frame 40 9 to permit a longitudinal movement of the slide 54. A single cap screw 56^a (Figs. 3 and 7) acts behind both the needle carrier 49 and the slide 54 to the lever 46. The slide 54 is provided with a cam opening 57 45 into which there projects a roll 58 carried by a small slide 59 (Fig. 6) mounted for vertical movement in a slot 60 in the knife frame 9 and held in position by a cap plate 61 (Figs. 4 and 6).

55 The feather or edge knife 11 is provided with a transverse opening 62 (Fig. 8) and the needle is arranged just opposite to and is adapted to pass through said opening in forming the stitch. The knife 11 is also 60 provided with a vertically arranged opening 63 which intersects the transverse opening 62. A groove at the inner side of the knife provides a recess for the thread. An eye-ended looper 64 is carried by the vertical slide 59 and is so arranged as to have

movement in the vertical opening 63 of the knife 11. The thread from the guide 38 passes through the eye of the looper 64. As the needle moves inward it passes through the channel and edge flaps which have been cut and are held upturned by the knives 1 and 11, and then into the opening 62 and past the opening 63. This movement of the needle carries the slide 54 with it and causes the surface marked *a* of the cam opening 57 to engage the roll 58 of the looper slide 59 and force said roll downward carrying the looper downward with it and into the opening 63 of the knife 11. This places the thread in position to be engaged by the needle and carried through the flaps to form a loop (see Fig. 8). On the backward stroke of the needle the roll 58 of the looper slide 59 is engaged by the surface marked *b* of the cam opening and the looper is again raised to its initial position, carrying the thread out of the path of the needle. The looper slide 59 is maintained in any position in which it may be placed by either of the cam surfaces *a* or *b* by reason of a friction device formed of a small pad or cup 65 (Fig. 6) of metal or other suitable substance placed in a recess in the slide 59 and held, by means of a small coiled spring 66, in contact with the cap plate 61.

The outer end of the slide 54 is provided with an oval-shaped opening 54^a. The forward and rear edges of the opening 54^a are adapted, in the movement of the slide 54, to engage a roll 68 (Figs. 3 and 7) mounted on the lower end of an arm 69 pinned to a stud 70 which is journaled in the outer end of the knife frame 9. The stud 70 projects from a second arm 71 (Figs. 3 and 4) provided at its free end with a slot 76. The knife frame 9 is provided with a curved guideway 77 (Figs. 4 and 5) extending on the arc of a circle having the fulcrum of the needle operating lever 46 as a center. This guideway, therefore, is of the same curvature as the needle 50. Mounted for movement in the guideway 77 is a slide 78 provided at its upper end with a pin 79 which projects into the slot 76 of the arm 71. The inner end of the slide 78 carries a cast-off 80 having an eye through which the needle 50 passes. The cast-off is also provided with a lip 81 (Figs. 4 and 5) for covering the barb of the needle as is necessary in performing its function.

The stitching mechanism described makes a chain-stitch in the usual manner. The needle is moved forward through the work, the looper is moved downward to bring the thread across the needle, so that it may be caught by the barb of the needle and carried through the work on the backward stroke to form a loop, the work is then fed with the loop still on the needle, and the needle again forced through the work, seizing the

thread to form a second loop and pulling it through the first loop, which is then cast off.

Owing to the short and rapid reciprocations of the needle and the nature of the work means should be provided to insure a spreading of the loop on the needle as the needle advances so as to insure a passage of the needle therethrough. It will be obvious to those skilled in the art that in sewing around the toe of an insole, where the turning of the work during the feed causes the loop of thread at times to stand in such a position to the line of movement of the needle that there is a liability of the needle passing outside of the loop instead of through it, a spreading of the loop as the needle advances will provide such an opening that the needle will always pass through the loop. To gain this end a bracket 82 (Figs. 4 and 5) is mounted on the knife carrying frame 9 provided with a spring pressed plunger 84 suitably mounted within a socket 83. The position of the plunger is such that it is engaged by the arm 71 of the cast off slide on the backward stroke of the needle, and at the outer limit of the needle stroke the plunger has been moved so as to place its spring under compression. Thus on the forward stroke of the needle the forward movement of the spring plunger 84 insures a retention of the cast off lip 81 over the needle barb until the loop carried by the needle has been spread sufficiently to insure a passage of the needle therethrough whatever position the loop may assume relative to the needle. The plunger 84 also acts to take up loose play in the parts and to overcome the shock incident to the reciprocation of the needle. Owing to the relation of the parts just described their operation is such that in making a stitch, as the needle passes forward to pierce the work it will first carry the cast off 80 with it for a short distance and will then pass through the cast off which at this time remains stationary, and the cast-off is not farther moved until the front edge of the opening 54^a in the slide 54 engages the roll 68 as in Fig. 5. After the roll 68 has been engaged, its arm 69 is moved forward, carrying with it the arm 71 which is engaged by the roll 79 of the cast-off slide 78. This causes the cast-off and needle to again move forward together and to so move during the remainder of the forward stroke. On the backward stroke the opening 54^a of the slide 54 provides the same loose play as on the forward stroke, so that the needle will first move through the cast-off, leaving the cast-off at the work in the position shown in Figs. 5 and 8. This movement of the needle continues until it has reached a position where its barb is covered by the lip 81 of the cast-off. At about this time the rear edge of the opening 54^a has

contacted with the roll 68 of the arm 69, and in a similar manner as before described, the arm 71 is moved and carries with it the cast-off slide 78, thus moving the cast-off and needle simultaneously from this point 70 during the remainder of the backward stroke.

The operation and timing of the working parts of the machine are such that the successive stitches are formed during the cutting and upturning operation and are placed immediately adjacent the junction of the forward end of the severed flaps and the insole. Thus a fastener is applied to the upturned flaps as soon as they are in a position to receive it. This insures speedy work and a large output from the machine.

Referring now again to Fig. 1, the lug 120 of the work support slide 37 is embraced by a block 100, which block is pivoted to one arm of a bell crank lever 101 fulcrumed at 102 on the frame F. The other arm of this bell crank is pivoted to a slide 103 guided in horizontal ways 104 on the frame F. To the slide 103 is adjustably connected a thread-cutting knife 105. The construction is such that the knife 105 is in retracted or inoperative position while the work support 35 is raised and the sole is being operated upon. On lowering the work support to remove the sole the bell crank lever 101 is turned in a direction to move the knife forward across the feather knife 11 to sever the thread at the back of said feather knife.

The knives 1 and 11 are provided with means to limit the depth of cut which they make, which means is conveniently in the form of a presser-foot. In the present instance there is provided a single presser-foot for both of the knives, which presser-foot extends adjacent the cutting edges of the knives and bears on the between substance just in front of said cutting edges. In the present form of the invention the presser-foot is carried by a vertically movable bar 90 (Figs. 2 and 6) which is sustained in a guideway of a support 91. The support 91 is mounted, for in-and-out movement of the presser-foot relatively to the knives, in a guideway 92 of the shank 25 which supports the knife carrying frame 9. The support 91 is split adjacent the guide for the presser-foot bar 90 and the presser-foot bar is held in its guide by means of a clamping screw 93 which draws the split support together. The presser foot bar 90 is adjusted vertically by rotating a screw 94 (Fig. 6) provided with peripheral teeth adapted to engage with a rack 95 on said presser-foot bar. The bearing surface of the presser-foot is formed of a number of small rollers 96 on a stud 97 at the bottom of the bar 90 and extending transversely across the cutting edges of the 130

knives. Rollers are used, as a convenient anti-friction bearing surface for the presser foot is thus provided, and preferably a number of rollers are used as a bearing foot so constructed aids the turning of the sole during its feed through the machine. On turning the sole it is swung about the channel knife as a fulcrum, and this fulcrum is located at about the center of the 10 presser-foot. Therefore, a series of rolls extending on opposite sides of the fulcrum point will permit a movement of parts of the presser-foot in opposite directions according to the direction of movement of the 15 particular portion of the sole on which any one of the series of rolls bears.

Referring now to Fig. 6 it will be seen that the edge or feather knife block 12 is held in the guide 15 of the knife carrying 20 frame 9 by means of a collar screw 13 as in the patent to William C. Meyer referred to. Unlike the machine of said application, however, the knife block is slotted at the point where the screw 13 passes through it in a 25 manner to permit an adjustment of the knife block toward and from the presser foot 96. A headed screw 14 (Figs. 3 and 6) is threaded into the knife carrying frame and the knife block is provided with a groove 16 30 (shown best by the dotted line in Fig. 7) to be engaged by the head of said screw. With this construction, by loosening the screw 13 the edge knife block may be adjusted relatively to the presser foot by a rotation of the screw 14. This adjustment is desirable to take up the wear of the knife and thus always insure a pressure of the 35 presser foot 96 immediately adjacent the edge of the knife. It has been found in practice that if the pressure from the presser foot is not applied at the point of cutting, the margin of the sole between the edge of the knife and the presser foot will curl up and permit the knife to dig into the feather 40 and sometimes to cut through it completely thus spoiling the insole. The reason for using rolls of small diameter on the presser foot will now be clear. If the rolls are 45 comparatively large it would be impossible to place the edge of the knife sufficiently close to the pressure point to prevent the curling up of the sole above referred to.

To sharpen the knife the block 12 is completely removed from the frame 9 and the tongue and groove connection, formed by the headed screw 14 and groove 16, always insures that the knife block is replaced in exactly the same position relatively to its support and adjacent parts as before its removal. The head screw 14 forms an adjustable index which coöperates with the groove 16 for determining the position to be assumed by the knife on replacement and the screw 13 locks the block securely in the 60 position determined by the index.

The channel knife block 3 is mounted and is adjustable on the knife carrying frame 9 in a similar manner to that described for the edge knife block. The movement of the channel knife is relative to the edge 70 knife for varying the thickness of the between substance.

Nothing herein contained is to be construed as limiting this invention in the scope of its application to use in connection with 75 the particular machine or particular mode of operation, or both, selected for purposes of illustration and explanation. While the particulars of construction herein set forth are well suited to one form of the invention, 80 it is not to be understood that these particulars are essential, since they may be variously modified within the skill of the artisan without departing from the true scope of the actual invention as defined in the following 85 claims.

What is claimed as new, is:—

1. In a machine for making insoles, the combination with a support for an insole blank and devices for engaging and upturning two contiguous flaps cut from the substance of one face of the blank, of means for successively inserting fastening devices in said flaps adjacent the upturning devices and during the operation of said devices to 95 form a permanent compound lip on the insole blank.

2. In a machine for making insoles, the combination with means for cutting and upturning two contiguous flaps, of a stitching 100 mechanism, and means to operate said mechanism to stitch said flaps together during the operation of the cutting and upturning means to form a permanent compound lip.

3. In a machine for making insoles, the combination with a channel knife and an edge knife for cutting two contiguous flaps, and means for holding said flaps in upturned position, of a sewing mechanism for stitching said flaps together, one of said 105 knives being constructed and arranged to permit the needle of the sewing mechanism to pass through it, thereby to form the stitch immediately adjacent the junction of the forward ends of the severed flaps and 110 insole.

4. In a machine for making insoles, the combination with means for holding the sole in working position, of means for securing the two contiguous flaps together by 115 a line of stitches to form a single, compound lip, and means under control of the operator for simultaneously releasing the sole and severing the thread at the completion of the stitching operation.

5. In an insole machine the combination with means for securing the two contiguous flaps together by a line of stitches to form a single, compound lip, of a device for severing the thread, a work support construct. 120 125 130

- ed and arranged to be moved to facilitate removal of the work, and means controlled by the movement of the work support for operating the thread-severing device.
5. 6. In an insole machine, the combination with means for securing together the two contiguous flaps by a line of chain stitches to form a single, compound lip, including a barbed needle and a cast off, of provision
- 10 for holding the cast off over the needle barb during a portion of the forward movement of the needle to insure a spreading of the needle loop and thus facilitate a passage of the needle therethrough.
- 15 7. In an insole machine, the combination with means for securing together the two contiguous flaps by a line of chain stitches to form a single, compound lip, including a barbed needle and a cast off, of a single
- 20 means for operating the needle and cast off including the provision of loose play to permit a movement of the needle relatively to the cast off at the beginning of its forward and backward movements, and a spring to
- 25 be engaged and compressed by the cast off on the latter portion of its backward movement while covering the needle barb, whereby expansion of the spring as the needle moves forward permits a retention of the
- 30 cast off in its position over the needle barb during a portion of the forward movement of the needle.
8. A machine for making insoles, having, in combination, a work support, means for cutting and upturning two contiguous flaps from the substance of the insole, and provision for applying to said flaps during the cutting operation a series of fastening devices to form a permanent single, compound lip.
9. A machine for making insoles, having, in combination, means for cutting two contiguous flaps from the substance of the insole and for upturning said flaps from the face of the insole, and provision for securing said flaps together to form a single lip by successive insertions of a suitable fastening device adjacent the point of operation of the cutting means.
10. A machine for making insoles, having, in combination, means for cutting and upturning two contiguous flaps from the substance of the insole to form a compound lip, and a fastener inserting mechanism co-operating therewith and operating to positively secure the two flaps together as they are placed in position to be secured by the cutting and upturning means.

In testimony whereof I affix my signature, in presence of two witnesses.

ALBERT E. JOHNSON.

Witnesses:

WARREN G. OGDEN,
ANNIE C. RICHARDSON.

It is hereby certified that in Letters Patent No. 1,109,759, granted September 8, 1914, upon the application of Albert E. Johnson, of Brockton, Massachusetts, for an improvement in "Machines for Making Insoles," an error appears in the printed specification requiring correction as follows: Page 5, line 61, for the word "head" read *headed*; and that the said Letters Patent should be read with this correction therein that the same may conform to the record of the case in the Patent Office.

Signed and sealed this 6th day of October, A. D., 1914.

[SEAL.]

R. F. WHITEHEAD,

Acting Commissioner of Patents.
